DISPENSER TOP FOR A PRESSURIZED CAN

Geoffrey Russell Stafford Charles, Marlow-on-Thames, England, assignor to Chelton (Electrostatics) Limited, Marlow-on-Thames, Buckinghamshire, England, a British company

Filed Nov. 18, 1966, Ser. No. 4,742

Term of patent 14 years

(Cl. D58—26)

FIG. 1.

FIG. 2.

FIG. 3.

FIG. 4.

FIG. 1 is a perspective view of a dispenser top for a pressurized can showing my new design;

FIG. 2 is a top plan view;

FIG. 3 is a bottom plan view; and

FIG. 4 is a sectional view taken on line 4—4 of FIG. 1.

I claim:

The ornamental design for a dispenser top for a pressurized can, substantially as shown.
